US00D580887S

(12) **United States Design Patent**
Beckert

(10) **Patent No.:** **US D580,887 S**
(b4) **Date of Patent:** **** Nov. 18, 2008**

(54) **BLADE FUSE AND FUSE ELEMENT**
THEREFORE

(75) Inventor: **James J. Beckert**, Rolling Meadows, IL
(US)

(73) Assignee: **Littelfuse, Inc.**, Des Plaines, IL (US)

(**) Term: **14 Years**

(21) Appl. No.: **29/321,735**

(22) Filed: **Jul. 22, 2008**

(74) *Attorney, Agent, or Firm*—Bell, Boyd & Lloyd LLP

(57) **CLAIM**

The ornamental design for a blade fuse and fuse element therefore, as shown and described.

DESCRIPTION

FIG. 1 is a front perspective view of a blade fuse and fuse element therefore, showing my new design.

FIG. 2 is a front view thereof.

FIG. 3 is a rear view thereof.

FIG. 4 is a side view thereof.

FIG. 5 is a top view thereof; and,

FIG. 6 is a bottom view thereof.

The broken line portion of the figure drawings is included to show unclaimed subject matter only and forms no part of the claimed design.

1 Claim, 3 Drawing Sheets
